Primary Examiner — Barbara Fox*Assistant Examiner* — Holly E Thurman(74) Attorney, Agent, or Firm — Lewis Kohn & Walker
LLP; Kent M. Walker; Kari Moyer-Henry(57) CLAIM

The ornamental design for goggles, as shown and described.

DESCRIPTION

1. Goggles

Fig. 1.1 is a front elevation view of goggles showing the new design;

Fig. 1.2 is a perspective view thereof;

Fig. 1.3 is a left side view thereof;

Fig. 1.4 is a right side view thereof;

Fig. 1.5 is a bottom plan view thereof;

Fig. 1.6 is a top plan view thereof; and

Fig. 1.7 is a back elevation view thereof.

The “JUST1” symbol forming part of the claimed design is a registered trademark of H&H Sports Protection.

1 Claim, 7 Drawing Sheets(56)
